ELECTRIC LAMP AND MOUNTING
THEREFOR

Walter J. Geiger, Cleveland Heights, and Alfred T. Gaskill, Cleveland, Ohio, assignors to General Electric Company, a corporation of New York

Application April 6, 1933, Serial No. 664,748

4 Claims. (Cl. 240—41)

Our invention relates to mountings for electric lamps and the like, and is especially adaptable and useful in cases where the light source should occupy a definite position with reference to some associated part or structure, such as a reflector or a lens. The invention is of particular advantage for projection lamps such as vehicle headlamps, in which an incandescent filament lamp is mounted in a reflector such as the well-known 10 paraboloid reflector.

In headlamps as at present constructed, the lamp is mounted by inserting its "bayonet" base in a tubular "bayonet" socket which is itself mounted in an opening at the apex of the reflector, with suitable provisions for adjusting the socket relative to the reflector to "focus" the light source of the lamp to exactly the right position for any desired distribution of light. While this arrangement permits easy removal and replacement of a lamp as well as accurate focusing, yet it is mechanically complicated, and often liable to derangements which allow the lamp to shift out of focus.

To overcome these disadvantages of present practice, we prefer to mount the lamp base more directly on the reflector, without the intervention of a socket and adjusting means therefor. This we do in such a way that when a given lamp is once properly focused in a reflector, this adjustment becomes permanently fixed; although the particular lamp can still be removed and replaced as often as desired,—for cleaning of the lamp or its reflector, etc. In this way, we are able to dispense with the usual lamp socket, as well as with its focusing mechanism.

For removably mounting the lamp, we provide its base with engagement means adapted to engage in perfectly definite relation with an accurately located and fixed part or engagement means of the reflector, provision being also made for holding these parts in proper engagement. This requires of course that the engagement means on the base be properly adjusted and fixed relative to the light source; and while this may be accomplished by extreme accuracy in the basing of the lamp, yet we prefer to embody the engagement means of the base in a separate part or "adapter" that can be properly adjusted on the base in focusing and permanently fixed thereto,—as by soldering, or other methods of forming a fused joint. The lamp 10—or, more properly speaking, its base with the properly focused adapter thereon—is inserted in an opening in the apex of the reflector, and the adapter is held properly engaged with the reflector by novel spring actuated means associated with the latter. Further features and advantages of our invention will appear from the following description of species thereof and from the drawing.

In the drawing, Fig. 1 is a partially sectioned elevation of a headlamp employing a form of mounting comprising our invention; Fig. 2 is a disassembled perspective view of the mounting and lamp; Fig. 3 is a side view in section of electrical connection means for the lamp; Fig. 4 is a side view of a modified form of adapter; and Fig. 5 is a plan view thereof.

Referring to Figs. 1 and 2, the lamp, indicated generally by the numeral 10, comprises a bulb 11 having a filament 12 sealed therein and mounted on leading-in wires 13. A base 14 comprising a tubular shell 14' is mounted on said bulb 11, and carries a terminal pin 15 mounted in insulating material 16 and protruding rearward beyond the end of said base. One of the leading-in wires 13 is connected to the base shell 14' and the other is connected to the pin 15. On the base 14 is mounted an adapter 17. This adapter 17 has an enlarged tubular portion 18 which fits in a hole 19 in a flattened portion 20 at the apex of the reflector 21. The enlarged portion 18 tapers down rearward to a comparatively narrow tubular portion 22, which surrounds the base 14. A flange 23 is formed at the forward end of the portion 18, adjacent the lamp 10, for determining the longitudinal and axial position of the lamp in the reflector opening. The adapter 17 has engagement means for locking the lamp 10 against turning in the reflector opening (as hereinafter described), such as a rearwardly projecting lug 24 on the rim of said flange. The adapter 17 is located on the base 14 so that the rear surface of the flange 23 bears a definite relation to the filament 12, the reduced adapter portion 22 being of slightly larger diameter than the base, so that the lamp may be rocked in the adapter to locate the filament both axially and longitudinally, and may also be turned to locate it angularly with reference to the lug 24. When the filament 12 has been thus prefocused, the adapter 17 is fixed to the shell 14', preferably by solder 25.

The lamp 10 is placed in the reflector 21 so that the rear surface or shoulder of the flange 23 bears against the inside surface of the flattened portion 20, which is definitely located with respect to the focal point of the reflector, and the lug 24 enters a seat formed by a recess or opening 26 in said reflector—thus definitely locating the filament to give the desired distribution of light. The flange 23 is held against the reflector by spring-actuated retaining means, hereinafter described, which engage an annular retaining lip 27 on the rear end portion 22 of the adapter 17. The retaining lip 27 is beveled at its rear surface, and presents a square shoulder forward, toward the bulb. It is no larger, at least, than the portion 18, which may fit the opening 19 easily but without play.

The spring-actuated retaining means for engaging the adapter shoulder at 27 are distributed around the lamp base opening 19 of the reflector 21, and in the present instance have the character of independent spring catches embodied in a spring holder 28 mounted on the rear of the reflector portion 20. The spring holder 28 comprises a flat annular portion 29 with a hole 30 therein of substantially the same diameter as the hole 19 in the reflector 21. This holder 28 is held on the reflector by a pair of oppositely located lugs or tongues 31 which engage in holes 32 in said reflector. A plurality of retroverted or bowed spring fingers 33 (three being shown) extend outward, rearward, and inward again from the periphery of the portion 29, and have rearward bent latch tips 34 at their ends. These tips 34 of the spring catches 33 coat with the rear bevel on the annular lip 27 of the adapter 17, as well as with its front shoulder; i. e., when the catches 33 snap over the lip 27 and engage behind its shoulder they are held there, besides holding the lamp base 14 pressed home in the reflector opening 19, with the flange 23 firmly against the flattened portion 20 of the reflector all around the opening 19. A slot 35 is provided in the rim of the holder portion 29 corresponding to the opening 26 in the reflector, to accommodate the lug 24. The lug 24 not only locks the lamp 10 in proper angular relation to the reflector 21, but also makes it virtually impossible to secure the lamp in any wrong angular relation, because of the impossibility of engaging the spring catches 33 under the lip 27 unless the lug 24 is seated at 26.

Obviously the insertion-limiting shoulder or flange of the adapter need not be continuous as in Fig. 2; on the contrary, it may be interrupted even to the extent shown in Figs. 4 and 5, where three properly distributed arms or lugs 36—37—38 are substituted for the flange 23, an anti-turning key lug 39 similar to lug 24 being provided on lug 36. It may be preferable to employ such lugs in view of the fact that a solid flange is liable to warp.

Electrical connection may be made to the lamp 10 by a helical spring connector 40 (Fig. 3) which is slipped over the pin 15 of the lamp. Said connector 40 comprises a helical spring 41, one end 50 of which is clamped on a metal sleeve 42 mounted on the end of the insulating covering 43 of a stranded conductor 44 which is in contact with said sleeve. The spring 41 is deformed so that the axis thereof is not a straight line. In the preferred form a number of turns 45 at the opposite end of said spring 41 are offset axially with respect to the remaining turns, thus insuring a firm contact of said spring with the pin 15 which brings the axis of the spring back to a straight line. An insulating covering 46, preferably a soft rubber tube, surrounds the said spring 41.

In Fig. 1 is shown a complete headlamp, wherein the reflector 21 is located in a housing 47. The said reflector is held by a flange 48 thereon, either by screws (not shown) or by a retaining ring 49 which also holds a lens 50 over said reflector. The conductor 44 extends through an insulating washer 51, mounted in a hole in the housing, to the switching and battery equipment. To remove a lamp 10, the reflector 21 is removed from the housing 47, the connector 40 is detached, and

then the retaining springs 33 are pressed forward and drawn outward to release the fingers 34 from the lip 27, allowing the lamp to be removed from the reflector. The released springs 33 expand rearward and assume the position of the upper spring shown in dotted lines in Fig. 1. To re-engage the springs 33 with the lip 27, it is only necessary to press forward and inward on their ends until their fingers 34 snap past and under the beveled lip. 10

What we claim as new and desire to secure by Letters Patent of the United States is:

1. The combination of a reflector having a lamp base opening therein, with a lamp comprising a bulb and a base having a portion of substantially the same diameter as said opening with a lateral projection thereon forming an external shoulder seating directly in said reflector opening, said lateral projection engaging one side of the margin around the said opening in said reflector, another external shoulder on said base on the opposite side of said reflector, and a spring disposed between said reflector and said second mentioned shoulder and exerting a pressure axially of the lamp to hold said lateral projection against said reflector margin. 20

2. The combination of a reflector having a lamp base opening therein, with a lamp comprising a bulb and a base having a portion of substantially the same diameter as said opening with a lateral projection thereon adjacent said bulb forming an external shoulder seating directly in said reflector opening, said lateral projection engaging the inside of the margin around the said opening in said reflector, another external shoulder on said base behind said reflector, and a spring disposed between the back of said reflector and said second mentioned shoulder and exerting a pressure rearwardly of the lamp to hold said lateral projection against said reflector margin. 40

3. The combination of a reflector having a lamp base opening therein, with a lamp comprising a bulb and a base having an enlarged portion of substantially the same diameter as said opening with a lateral projection thereon adjacent said bulb forming an external shoulder seating directly in said reflector opening, said lateral projection engaging the inside of the margin around the said opening in said reflector, another external shoulder on said base behind said reflector not exceeding the said enlarged portion in size, and a spring disposed between the back of said reflector and said second mentioned shoulder and exerting a pressure rearwardly of the lamp to hold said lateral projection against said reflector. 50

4. An electric lamp comprising a bulb and a base and an adapter fixed on said base in focus adjustment, said adapter consisting of a metal shell comprising an enlarged cylindrical portion at one end with a lateral projection on one end thereof forming an external seating shoulder, a reduced cylindrical portion adjacent the opposite end of said enlarged portion surrounding said base and secured thereto, and an outwardly beveled lip at 60 the end of the said reduced portion of said adapter constituting a shoulder facing said first mentioned shoulder and not exceeding said enlarged portion of said adapter in size. 65
